ADJUSTING AND OPERATING MECHANISM
FOR ENCLOSED INK FOUNTAINS

Adolph Weiss, Brooklyn, N. Y.

Application May 23, 1936, Serial No. 81,409

36 Claims. (Cl. 101—157)

The present invention relates to rotary intaglio printing presses having enclosed fountains within which ink is adapted to be received and applied to the printing cylinder which is partially enclosed by the fountain. In applicant's patents Reissue No. 18,856 granted June 6, 1933, and No. 2,014,303 granted September 10, 1935, there is shown and described an enclosed fountain of the above character.

10 The present invention has for an object the provision of a fountain of the above character, the construction of which is greatly simplified, and the control and maintenance of which is greatly facilitated.

15 A further object of the invention is to provide a construction of the above character in which the control elements are effectively protected and separated from the ink and ink vapors present within the housing.

20 A further object of the invention is to provide a housing in which the upper portions are so constructed and positioned that interference with the web and with access to the press is prevented.

25 A further object of the invention is to provide, in combination with a housing having an inking head, means for automatically draining the ink from the head prior to the removal of the head from the fountain.

30 A further object of the invention is to provide a housing of the above character having a construction such that the exterior surface is formed with a minimum number of projections, thus facilitating the cleaning and maintenance thereof.

35 A further object of the invention is to provide, in combination with an enclosed fountain having means to apply ink directly to the cylinder, mechanism by means of which the inking device may be effectively controlled while preserving a 40 desired closure about a portion of the cylinder.

A further object of the invention is to provide an inking device in combination with structure of the above character by means of which the position of the inking device may be effectively 45 varied by movement thereof in one or more directions in order that the device may be properly positioned with respect to printing cylinders of varying diameters.

A further object of the invention is to provide, 50 in combination with means for moving and adjusting the position of the inking head of fountains of the above character, means by which the fountain may be effectively locked in a desired position.

55 A further object of the invention is to provide

a control mechanism for fountains having an inking head, the mechanism affording a sequential operation such that improper steps cannot be taken in assembling or dismounting the head. In this connection, it is proposed to provide a 5 control by means of which the drain for the head is first opened by the operation of removing the head, and, after the drain has been opened, further continued operation of the control mechanism releases the felt sealing member, after 10 which the head is unlocked.

A further object of the invention is to provide, in combination with an enclosed fountain of the above character, doctor mechanism and operating means therefor, together with means for 15 mounting the doctor and associated elements in such fashion as to permit them to be readily and quickly moved from a normal operating position to a retracted position and vice versa, without requiring the exercise of care when the doctor 20 is returned to its proper normal wiping position.

A further object of the invention is to provide, in combination with doctor mechanism of the above character, means for effectively adjusting and locking the doctor in a desired position with 25 out destroying the enclosure about a portion of the cylinder.

A further object of the invention is to provide a doctor adjusting and locking mechanism of the above character in combination with a driving 30 connection for reciprocating the doctor, such driving connection being preserved at all times regardless of the position of the doctor mounting mechanism.

A further object of the invention is to provide 35 a doctor reciprocating mechanism which serves not only as the driving and reciprocating means for the doctor, but also as a means upon which the doctor is mounted for rocking motion hinged-ly from a wiping to a retracted position.

A further object of the invention is to provide, in combination with an enclosed housing of the character above described, an improved sealing mechanism by means of which the ends of the housing may be effectively sealed, the construction being such as to avoid excessive wear between 45 relatively moving parts.

A further object of the invention is to provide, in combination with an enclosed housing, end sealing mechanism by means of which an effective seal may be preserved between the end of the cylinder and the housing end wall, and between the reciprocating doctor and a sealing means upon the side of the cylinder opposite from the doctor.

A further object of the invention is to provide a mechanism by means of which ink which accidentally escapes from the housing, is prevented from reaching control mechanism therefor. In 5 this connection, the control mechanism is so positioned that it is out of the path of flow of such escaping ink.

A further object of the invention is to provide, in combination with a doctor control mechanism, 10 an indicator by means of which the wiping pressure of the doctor may be indicated.

A further object of the invention is to provide a construction wherein the wiping mechanism is supported upon a relatively rigid supporting 15 structure.

Further objects of the invention will be apparent as it is described in connection with the accompanying drawings, wherein

Figure 1 is a view in side elevation of a housing constructed in accordance with the present invention and looking at the inking side of the housing;

Figure 2 is a plan view of the inking side of the housing shown in Figure 1 with a portion 25 of the inking head broken away and in section to illustrate the manifolding of the inking head;

Figure 3 is a view in section, taken on line 3—3 of Figure 1, and looking in the direction of the arrows;

Figure 4 is a view in section, taken on line 4—4 of Figure 1, and looking in the direction of the arrows;

Figure 5 is a view in section, taken on line 5—5 of Figure 4, and looking in the direction of the arrows;

Figure 6 is a view in section, taken on line 6—6 of Figure 4 and looking in the direction of the arrows;

Figure 7 is a view in side elevation showing 40 the doctor side of the ink housing of a fountain constructed in accordance with the present invention;

Figure 8 is a view in side elevation, taken from the interior of the ink housing, and showing the 45 improved end seal mechanism constructed in accordance with the present invention;

Figure 9 is a view in section, taken on line 9—9 of Figure 8, and looking in the direction of the arrows;

Figure 10 is a view in section, taken on line 10—10 of Figure 7 and looking in the direction of the arrows;

Figure 11 is a view in section, taken on line 11—11 of Figure 7 and looking in the direction 55 of the arrows;

Figure 12 is a view in section, taken on line 12—12 of Figure 10 and looking in the direction of the arrows, this view illustrating the hinge mechanism by means of which the cover is mounted 60 on the apron;

Figure 13 is a view in section, taken on line 13—13 of Figure 11 and looking in the direction of the arrows, this view illustrating the lock mechanism between the apron and the stationary 65 portion of the doctor mounting mechanism;

Figure 14 is a view in section, taken on line 14—14 of Figures 1 and 7 showing the elements of the housing in assembled relation;

Figure 15 is a view in section, taken on line 70 15—15 of Figure 3 and looking in the direction of the arrows;

Figure 16 is a view in section, taken on line 16—16 of Figure 7, and looking in the direction 75 of the arrows, this view illustrating the indicat-

ing mechanism by means of which the wiping pressure of the doctor may be indicated; and

Figure 17 is a plan view of the end seal mechanism illustrated in Figures 8 and 9.

With reference to the above drawings, the housing will be seen to include a sump 20 (Figure 14) having side walls 21 and 22. A pipe 23 communicates with the lowest position of the sump and permits ink to be withdrawn therefrom by a suitable pumping and recirculating mechanism 10 as shown particularly in applicant's Patent No. 2,014,303 above referred to.

Upon the side wall 21 is formed an inwardly extending horizontal flange 24, having an angularly extending flange 25. The side wall portion 15 or wall plate 26 is formed with a horizontal table 27 upon which one or more guide rods 28 are secured.

The guide rods 28 are mounted upon a longitudinal bracket forming a hinged side wall portion 29 having a base portion 30 adapted to engage the plate 24 when the mechanism is in its normal operating condition, as illustrated in Figure 14 to form cooperating longitudinally extending sealing surfaces. The bracket 29 is formed 25 with a plurality of pairs of spaced hinge arms 31 which cooperate with apertured bosses 32, formed upon the side walls 21 and, with hinge pins 33, serve to mount the table 27 and bracket 29 hingedly in order that the structure may be 30 swung away from its normal position to facilitate access to the fountain.

In order that the guide rods 28 may be properly positioned, guides 34 are formed on the bracket 29 being connected thereto by means of webs 35. The guides 34 are formed with guide ways 36 within which the guide rods 28 are slidably received, the guide rods being formed with teeth 37 which are adapted to be engaged by gears 38, mounted upon a shaft 39. The shaft 39 is journaled in bosses 40, also formed on the webs 35, thus providing a means by which all of the guide rods 28 are moved simultaneously. This motion results from an operating mechanism mounted intermediate the ends of the bracket 29 and including a housing 41 which is secured to bosses 42 and 43, formed upon the bracket 29 and base plate 30, respectively. A drive shaft 44 is journaled in the housing 41 and bracket 29, being provided with a squared end 45 and a worm 46. A worm wheel 47 is splined to the shaft 39, thus transmitting power from the drive shaft 44 to the shaft 39 and gears 38. In this fashion, the guide rods 28 are moved in either direction vertically to adjust the vertical position of the wall 26.

Upon the horizontal table 27 a reentrant retaining flange 48 is provided, an inking head 49 being received upon the table. The head 49 is formed with a base 50 having an elongated groove to receive the flange 48 and be locked thereby. The base 50 is formed with spaced recesses 51 adjacent the ends thereof, such recesses serving to receive locking mechanism to be presently described. The head 49 and base 50 are secured together by means of bolts 52 and the head is locked in the position shown in Figure 4 by means of a cam 53 (Figure 6) which is mounted upon a vertical shaft 54, journaled in a boss 55 which is formed on the head 49. The shafts 54 have pinions 56 secured to the upper ends thereof, these pinions engaging a rack 57 (Figures 1, 2, 3, 4 and 14) which is slidably mounted in bosses 58 formed in the head 49 and provided with grooves 59 within which the rack 57 is slidably mounted.

The rack 57 is also shown in Figure 14 wherein the mechanism by means of which the locking cams 53 are operated is illustrated in greater detail. For this purpose, a shaft 60 is mounted in 5 the head 49 and provided with a manually operable crank 61 as well as a pinion 62 which engages the teeth of the rack 57. By turning the crank 61, the rack 57 may be moved in either direction, causing the shafts 54 and cams 53 to be turned. 10 Upon opposite sides of each of the shafts 54, and lying substantially in planes passing through the axes of shafts 54 and perpendicular to the wall 26 are stub shafts 63 and 64 secured in the platform 27. Stub shaft 63 is provided with a roller 65 15 while shaft 64 is provided with a roller 66 having a flanged portion 67. Each of the cams 53 is formed with a tapered surface 68 which is adapted to be engaged under the flanged portion 67 to lock the head in the position shown in Figure 4. 20 When the rack is moved in either direction from the position shown in Figure 4, the cams 53 are turned and, upon motion thereof through 180 degrees, the rollers 65 are engaged and the base 50 is retracted from the flange 48 to unlock the 25 head and permit the same to be removed.

In order that the fountain may be effectively sealed to prevent substantial evaporation of the volatile ingredients of ink that may be used in the housing, the head 49 is provided with a 30 movable bracket 69 which is locked in a normal sealing position by means of a spring lock plate 70. To this end, the bracket is formed with a plate 71 having a positioning flange 72. The head 49 is formed with a longitudinal shoulder 73 35 against which the flange 72 abuts to position the bracket 69 properly with respect to the head. Within the bracket 69 is provided a sealing strip 74 of any suitable material such as felt, or the like, this strip being secured to the bracket 69 by 40 means of screws 75 or the like. A positioning strip 76 is also provided within the bracket 69, screws 77 securing the same in position in order that the positioning strip 76 may maintain the sealing strip 74 effectively in the sealing position shown in 45 Figure 4. The positioning strip 76 is formed with a cutaway portion 78 along the portion thereof adjacent an ink discharge nozzle 79 (Figures 3 and 14) to be described in greater detail hereinafter. The end of the head 49 adjacent the 50 cylinder is formed with a boss 80 against which the bracket 69 urges the sealing and positioning strips 74 and 76 when the locking strip 70 has been moved to a locking position.

It will thus be seen that the bracket 69 may be 55 readily removed from the head 49 when the spring lock strip 70 is moved into a retracted position. In the normal position of the spring strip 70, however, as illustrated in Figures 3 and 4, the bracket is maintained in a normal sealing position. The 60 mechanism for actuating the locking strip 70 comprises eccentrics 81 secured to the shafts 54. Links 82 are formed with apertures 83 which receive the eccentrics 81 and thus transmit reciprocating motion from the rotating shafts 54 to the 65 links 82. At the other ends of links 82, apertured bosses 84 are provided, these bosses receiving stub shafts 85 which extend through a sealing plate 86 carried by the head 49, this plate being formed with apertures 87 to receive the shafts 85. 70 Above the sealing plate 86, the shafts 85 are provided with guides 88 which are received in grooves 89, formed within the head 49. Guides 88 are so mounted with respect to apertures 87 that the apertures 87 are closed when the lock plate 70 75 is in clamping position. The head 49 is also

formed with slots 90 in which the shafts 85 are slidably received, bushings 91 being provided therein for this purpose. A reinforcing strip 92 is provided beneath the spring locking strip 70, nuts 93 securing the foregoing elements in the 5 assembled position shown in Figure 4.

It will thus be seen that, when the eccentric locks 53 are disengaged, the lock strip 70 will be retracted to permit the bracket 69 to be removed. The foregoing operations occur simultaneously 10 inasmuch as the mechanism by means of which each operation is accomplished is actuated by the common manually operated crank 61.

Intermediate the ends of the head 49 ink channels and ducts are provided to supply ink to the 15 nozzle 79. Within the head 49 is secured a manifold member 94. The head 49 is secured, as illustrated in Figure 14, to the bottom plate 50 by the bolts 52 and the manifold member 94 is secured to the upper portion of the head 49 by 20 means of bolts 95. The sealing plate 86 extends longitudinally of the head and lies between the manifold member 94 and the upper portion of the head to serve as a means to seal the manifold member from the adjacent portions of the head 25 to which the said member is secured. Bolts 96 additionally secure the manifold member to the head and, by extending through the member, also secure elbow connections 97 to the manifold member. Flanges 98 are formed on the elbow 30 connections 97 and are secured to the outer wall 99 of the head 49 by means of bolts 100. As illustrated in Figure 2, the manifold member is formed in a plurality of sections as indicated by the division lines 101. Each section is formed 35 with an outer lip 102 which coacts with the adjacent portion of the head to form the nozzle 79. In order that a uniform amount of ink may be supplied to the nozzle over the entire length thereof, the manifold member is formed with 40 passages 103 which communicate with ducts 104. Ducts 104 in turn communicate with ducts 105 which, in turn, communicate with ducts 106. Ducts 106 communicate with ducts 107 which in 45 turn communicate with the nozzle 79, thus affording an even distribution of ink to the portion of the nozzles supplied by such ducts. Obviously, the cross sectional area of these ducts diminishes as the ducts progress to the various stages of division of the ink flow. The passages 103 are 50 supplied with ink from a manifold 108, formed in the elbow 97 (Figure 2). Each of the elbows 97 is formed with a flange 98 which is elongated and formed with a similar elbow, as shown in Figure 2. A longitudinal duct 109 is formed in 55 the flange 98, this duct communicating through a passage 110 with a manifold passage 111, formed in the side wall 99 of the head 49 (Figures 2 and 14). A pipe connection 112 with the manifold passage 111 permits ink to be delivered 60 to the said passage from a suitable circulating mechanism, not shown.

Within the side wall 9, and serving as a wall of the manifold passage 111, is a plate 113 upon which the flanges 98 are mounted. The passages 65 110 are formed in plate 113 to afford communication between the passages 109 and 111 and the plate 113 is formed with a horizontal flange 114 (Figure 14) within which the lower end of shaft 60 is journaled. In order that ink may be bypassed around the nozzle 79, a conduit 115 is provided between the manifold passage 111 and the interior of the ink housing. A valve chamber 116 is formed in this passage and adapted to receive a valve plug 117 (Figure 14). A shaft 118 70 75

- is secured to the valve 117 and journaled in the flange 114, the upper end thereof being provided with a pinion 119 which engages a gear 120, secured to the shaft 60. In this fashion, when the manually operated crank 61 is actuated to release the head 49 from its sealing position and release the sealing bracket 69 from like position, the valve 117 is opened to by-pass ink from the manifold passage 111 to the ink housing.
- Upon the side of the housing opposite from the inking head 49, a doctor supporting mechanism is provided of improved construction. This mechanism is preferably mounted upon the housing side wall 22 which, for this purpose, is provided with an upwardly extending portion 121 having a horizontal flanged portion 122. The outer side of the wall 121 is formed with pairs of spaced guides 123 (Figure 7) each of which is bored at 124 to receive guide rods 125. The guide rods are formed with teeth 126 which are engaged by pinions 127 carried by a shaft 128 which is journaled in bosses 129 formed upon the respective guides 123. Intermediate the ends of the shaft 128 a boss 130 is formed upon the outer side of the wall 22. A housing 131 is secured to this boss by means of bolts 132, the housing receiving a worm wheel 133 which is secured to the shaft 128 and with which is engaged a worm 134. The worm 134 is secured to a stub shaft 135 which is journaled in a boss 136 formed on the housing 131, the outer end of the shaft 136 being squared at 137. Rotation of shaft 135 thus causes the guide rods 125 to be moved in the guide ways 124.
- Upon the upper ends of the guide rods 125, mounting heads 138 (Figures 7 and 11) are secured. These mounting heads are formed with journals 139 in which a shaft 140 is journaled. An arcuate wall plate or platform 141 is provided within the housing, the plate being formed with lugs 142 which are apertured to receive the shaft 140 and mount the plate 141 for rocking motion about the said shaft. The plate 141 is formed with a wall portion 143 which is adapted to engage the flange 122 and provide an effective seal between the wall portion 143 and the said flange. In this fashion, the plate 141 and wall 143 preserve an effective seal between the stationary portion of the ink fountain and the movable portion at the doctor side thereof.
- Upon the upper portion of the plate 141, apertured lugs 144 are provided to receive a rod 145. This rod serves as a mounting means for slide brackets 146 (Figures 7 and 10), the brackets being formed with apertured bosses 147 at one end thereof to receive the rod 145 and apertured bosses 148 at the other end thereof to be mounted upon the shaft 140. The brackets 146 serve as a mounting means for an apron 149 which is secured thereto by means of bolts 150. The apron is provided with a stub shaft 151 upon which a roller 152 is journaled. This roller is received in a cam groove 153, formed in a collar 154 which is secured to the shaft 140. Inasmuch as the bracket 146 is slidably mounted upon the rod 145 and shaft 140, rotation of the shaft 140 will cause the apron 149 and brackets 146 to be reciprocated through the groove and roller connection above described.
- The upper end of the apron 149 is provided with an elongated groove 155 within which a doctor holder 156 may be secured by means of clamps 157 and bolts 158 (Figure 14). The doctor holder is provided with a flexible doctor 159 which thus is caused to reciprocate in accordance with the

motion of the apron 149. A sealing blade 160 is secured to the top of the plate 141 and exerts an upward pressure against the doctor 159 as illustrated in Figures 10, 11 and 14, thus effectively sealing the doctor 159 to the plate 141.

As above noted, the plate 141 is adapted to rock upon the shaft 140 and, in order that it may be maintained effectively in the normal position shown in Figures 10, 11 and 14, a locking mechanism is provided as illustrated in Figures 7, 11 and 13. For this purpose, the mounting heads 138 are drilled to receive lock pins 161 slidably therein. The lock pins 161 are formed with gear teeth 162 with which pinions 163 engage, pinions 163 being formed upon stub shafts 164 which are journaled in the mounting heads 138. Manually operable cranks 165 are secured to the outer ends of the shafts 164 in order that the latter may be turned to move the lock pins 161. Ears 166 are formed upon bosses 142 of the plate 141 adjacent the end flanges 168. These ears are formed with bores to receive the lock pins 161 when the plate 141 is in its operative position and when the cranks 165 are operated. In this fashion, when the lock pins 161 are in the position illustrated in Figure 13, the apron 149 and plate 141 are locked in the position illustrated in the drawings. When the lock pins 161 are released, these elements may be swung upwardly into an open position.

In order that the doctor may be maintained effectively in wiping engagement with a printing cylinder, a pressure blade 169 is provided, this pressure blade being mounted upon a cover 170 which is pivotally mounted on the apron 149 by means of links 171 which are pivoted to the apron at 172 and to the cover at 173. The links 171 are formed with flat bearing surfaces 174 which are adapted to engage the top of apron 149 in the normal position of the mechanism as illustrated in Figure 10. The links are positioned against endwise displacement by flanges 149a formed on plate 149. The pressure blade 169, carried by the cover 170 is urged into the position shown in Figures 10, 11 and 14 by means of eccentric cams 175 which are mounted upon a shaft 176, journaled in brackets 177, carried by the cover 170. The cams are adapted to engage rollers 178 which are mounted upon brackets 179, carried by the apron 149, and rotation of the shaft 176 is effected by means of a worm wheel 180 (Figure 14), the worm wheel being splined or otherwise secured to the shaft 176 and engaged by a worm 181, formed upon a stub shaft 182 which is journaled in the cover 170. The stub shaft 182 extends downwardly from the cover and receives a knurled knob 183 in order that the stub shaft may be rotated to rotate the shaft 176. In this fashion when the cover has been swung into such position that the contact member 174 engages the apron 149, the knurled knob 183 is turned until the eccentrics 175 force the cover effectively into the closed position shown in Figure 10, at which time the pressure blade 169 engages the doctor 159 to force the same into the wiping position illustrated, at the same time causing the sealing blade 160 to be deflected, as illustrated in Figures 10, 11 and 14.

In Figure 10 the dot and dash lines illustrate the position of the cover when it has been swung back away from the apron to permit access to the latter. It will be seen, from Figure 12, that the hinge connection 173 includes the lock pin 170a which also serves as the hinge element by means of which the cover 170 is hingedly con-

nected to the link 171. Lock pin 170a of each hinge connection is formed with teeth 170b which are engaged by teeth 170c formed on a shaft 170d which is actuated by a manually operated crank 5 arm 170e.

In order that the ends of the housing may be sealed effectively, end seals are provided thereon, such end seals comprising arcuate plates 184 upon which gear sectors 185 are provided. This 10 structure is shown in Figures 8, 9 and 17. Housing end walls 186 are provided with apertures 187 in which shafts 188 are journaled, the shafts being formed, at their inner ends, with gear teeth 189 for engaging the respective gear sectors 185, the outer ends of the shafts 188 being provided with hand wheels 190. Each hand wheel 15 is provided with a friction lock comprising a spring pressed detent 190a riding in a groove 188a formed in the shaft 188. The arcuate sealing plate 184 is mounted upon an arcuate bracket 191, the outer periphery of which conforms to the curvature of the printing cylinder, the bracket being formed with a flanged portion 192 and a rib 193 which lies between the sealing strip 184 and the doctor 159. The plate 184 is formed 20 with a groove 194 within which the rib 193 is received, and is further formed with a parallel flanged portion 195 between which and the plate 184, the flange 192 is received. In this fashion, the plate 184 is mounted for sliding movement 25 about the axis of a printing cylinder 196 which is illustrated in Figure 9, as well as in Figures 3, 4, 10, 11 and 14. A flexible strip 184a is riveted to the under side of each plate 184. This strip 30 (Figure 17) lies under the overhanging portion of plate 184 and projects circumferentially thereof at 184b and abuts against the adjacent edge 192a of the flanged portion 192 of bracket 191. In this fashion the top surface of the flexible 35 strip 184a lies in the plane of the top surface 192b of the bracket 191. The strip 184a is coextensive with the plate 184 at the doctor end thereof and with the flanged portion 192 of bracket 191 on the inking side of the housing.

The portion 184b of the flexible strip and the adjacent portion of the flange 192 are received 40 under the sealing strip 74 and an effective seal between the strip, housing end wall and cylinder is thus preserved in view of the fact that the strip 45 74 does not move during operation of the press. Inasmuch as the doctor 159 reciprocates, the sealing plate 184 cannot lie beneath the doctor because of the objectionable wear resulting therefrom. In accordance with the present invention, 50 the hand wheel 190 affords a means by which the plate 184 may be advanced against the doctor 159 into abutting sealing engagement therewith (see Figures 8 and 17) when the latter has been moved to its wiping position, thus preserving an 55 effective seal between the housing end wall 186, cylinder 196, and doctor 159.

As illustrated in Figures 7 and 16, the shaft 176 is provided with a clamp 200 having an arcuate indicator dial 201 upon which suitable indicia 60 is inscribed. This dial is positioned within a curved portion 202 of the cover 170. An aperture 203 is provided in such curved portion in order that the indicia on the dial 201 may be viewed therethrough.

A sleeve 204 is provided on the shaft 176, and 65 secured to the bracket 177 which is fastened to cover 170, the shaft 176 being journaled in sleeve 204. Upon the sleeve 204 a bracket 205 is clamped, the bracket having a longitudinally extending arm 206 in which is received an arcuate 70

slot 207, formed in the dial 201. In this fashion, the arm 206 and slot 207 serve as a device for limiting the pressure to which the doctor is subjected by means of the manually operated knob 183.

By means of the pressure indicator construction above described, a permanent initial setting for a given size printing cylinder is provided, such initial setting serving to enable the position of the wiping mechanism to be adjusted 10 properly. In operation, a doctor knife 159 having a new wiping edge is mounted in the machine and the indicator 200 is moved until the first or zero number appears through the aperture 203 on the cover 170. The wall plate 141 is next 15 adjusted by means of the wrench end 137 until a clean wipe is obtained on the printing surface 196. During operation and as the edge of the doctor wears, the operator turns the knob 183 to 20 compensate for such wear until the indicator reaches the limit of its reading and until the arm 206 reaches the limit of slot 207. At this stage, the operator cannot apply more pressure to the 25 doctor because of the lock afforded by the arm and slot of the indicator. At this point the indicator shows the operator that the wiping edge of the doctor has been worn to its tolerable maximum and the reconditioning of the edge is now necessary. Having replaced the worn doctor with a reconditioned or new one, a clean wipe 30 will be obtained when the indicator is brought again to zero position, without having to readjust the wiping mechanism. In this fashion the initial setting may be considered as a permanent one as long as the diameter of the printing cylinder remains the same. Furthermore, by means 35 of the above indicator, the cover 170 may be moved and returned again into its normal operating position without affecting the pressure adjustment of the pressure blade 169. This is 40 done simply by restoring the indicator dial to the same number which existed at the time the cover was moved from its normal operating position. The zero position of the indicator may 45 be changed by movement of the dial upon the shaft 176 and the limit position afforded by the slot 207 may be changed by changing the position of the bracket carrying the arm 206.

It will thus be seen that the construction described herein provides an improved fountain 50 wherein the operating parts are enclosed and maintained away from the ink and ink vapors within the housing, the construction also being such as to facilitate the cleaning and maintenance thereof, particularly in view of the minimum 55 number of projections from the fountain housing. All locking members are convenient and accessible and the control mechanism is such as to insure a proper sequence of operations to prevent damage to the mechanism.

Moreover, the construction is such that no ink 60 which accidentally escapes from the housing can reach the moving and adjusting parts of the control mechanism. This is illustrated particularly in Figure 10 wherein the reciprocating mechanism for the doctor is maintained away from the arcuate plate 141 by means of the shaft 140 and 145. In this fashion, if the sealing blade 160 fails to effectively seal the doctor along the entire length thereof, and ink escapes at such faulty seal, it will 70 flow down the upper surface of the arcuate plate 141 and not contact the reciprocating and control portions of the doctor mechanism.

Moreover, inasmuch as the inking head as well 75 as the doctor mechanism is positioned more to

the side of the cylinder than above the same, ready accessibility to the press and web is afforded. Inasmuch as the ink does not drain from the head by gravity, the inner lock with the control member insures opening of the drain prior to removal of the head.

By providing the end seal mechanism of the above character, the end seal may be turned in one direction to enable the cylinder to be readily removed from the fountain, thus preventing interference with the removal and replacement of cylinders.

It will be further observed that the doctor and reciprocating mechanism therefor is mounted directly upon a stationary portion of the fountain, thus affording a rigid mounting for such structure. Figures 10 and 11 illustrate such construction.

From the foregoing it will be seen that an improved fountain structure has been provided by means of which a more effective seal may be attained, at the same time providing a more readily adjustable inking head, as well as a doctor operating and adjusting mechanism which may be more effectively operated and controlled. The interlocking and coacting mechanism in the inking head and the doctor mounting provides not only for simplified operation, but insures proper interaction of the parts and facilitates more effective control of the fountain.

While the invention has been described with specific reference to the construction shown in the accompanying drawings, it is not to be limited, save as defined in the appended claims.

35 I claim:

1. In combination with an ink housing for a rotary intaglio printing machine having a wiping means and a stationary side wall, a housing wall plate, means to mount the wiping means on the wall plate, means to mount the wall plate pivotally with respect to the side wall, means to vary the position vertically relative to the side wall of the pivot mounting of the wall plate, and cooperating longitudinally extending portions on the wall plate and side wall forming sealing surfaces adapted to maintain a seal therebetween in the various adjusted positions of the movable wall plate.

2. In combination with an ink housing for a rotary intaglio printing machine having a wiping means and a stationary side wall, a housing wall plate, means to mount the wiping means on the wall plate, means to mount the wall plate pivotally with respect to the side wall, means to vary the position vertically relative to the side wall of the pivot mounting of the wall plate, a longitudinally extending portion on the inner side of the side wall having a sealing surface thereon, and a flange on the wall plate extending downwardly from the pivot mounting thereof and having a sealing surface adapted to cooperate with the sealing surface on the side wall in the adjusted positions thereof.

3. In combination with an ink housing for a rotary intaglio printing machine having a wiping means and a stationary side wall, a housing wall plate, means to mount the wiping means on the wall plate, means to mount the wall plate pivotally with respect to the side wall, means to vary the position vertically relative to the side wall of the pivot mounting of the wall plate, a longitudinally extending portion on the inner side of the side wall having a sealing surface thereon, a flange on the wall plate extending downwardly from the pivot mounting thereof and having a

sealing surface adapted to cooperate with the sealing surface on the side wall in the adjusted positions thereof, and means to lock the wall plate in a normal position in which the sealing surfaces are in sealing engagement.

4. A wiping mechanism for a rotary intaglio printing machine comprising a pivoted platform upon which the wiping means is mounted, a reciprocable slide for the wiping means slidably mounted on the platform, a drive shaft and connection for reciprocating the slide, and means to guide the slide by the shaft and pivot the platform thereon.

5. A wiping mechanism for a rotary intaglio printing machine comprising a pivoted platform upon which the wiping means is mounted, a pivot shaft for the platform, journal supports for the shaft independent of the platform, and locking means between the platform and journals to lock the platform in a predetermined operative position of the wiping mechanism.

6. Wiping mechanism for an intaglio printing machine comprising a stationary side wall, a platform upon which wiping mechanism is adapted to be mounted, vertical guide members slidably mounted on the side wall, journal brackets on the guide members, and a fulcrum shaft for the platform journaled in the brackets, said guide members serving as means to adjust the operating position of the wiping means to accommodate printing cylinders of varying diameters.

7. Wiping mechanism for an intaglio printing machine comprising a stationary side wall, a platform upon which wiping mechanism is adapted to be mounted, vertical guide members slidably mounted on the side wall, a reciprocable slide on the platform upon which the wiping mechanism is mounted, journal brackets on the guide members, a drive shaft rotatably journaled in the brackets, a driving connection between the shaft and slide, and means to guide the slide on the shaft and mount the platform pivotally thereon.

8. A wiping mechanism for a rotary intaglio printing machine comprising a stationary side wall, an adjustable pivotally mounted platform for the wiping means, guide members adjustably mounted on the side wall, journal brackets carried by the guide members, a fulcrum shaft for the platform journaled in the brackets, and locking means to lock the wiping means in a predetermined position.

9. A wiping mechanism for a rotary intaglio printing machine comprising a stationary side wall, an adjustable pivotally mounted platform for the wiping means, guide members adjustably mounted on the side wall, journal brackets carried by the guide members, a fulcrum shaft for the platform journaled in the brackets, and locking means between the journals and platform to lock the wiping means in a predetermined position.

10. A wiping mechanism for a rotary intaglio printing machine comprising a pivotally mounted platform for the wiping means, a pivot shaft for the platform, journal brackets supporting the shaft, a lock plunger slidably mounted in a bracket, the platform being formed with a recess to receive the plunger, and means to actuate the plunger.

11. A wiping mechanism for a rotary intaglio printing machine comprising a stationary side wall, an adjustable mounting platform for the wiping means, a plurality of vertical guide members slidably mounted on the side wall, brackets

- carried by the guides, supporting means for the platform carried by the brackets, and common means for engaging the guide members for simultaneous movement thereof, to locate the wiping means in operative position for various cylinder diameters.
12. A wiping mechanism for a rotary intaglio printing machine comprising a mounting platform for wiping means, guide supports on the platform, a reciprocable slide carrying the wiping means and slidably mounted on the guides, and means to elevate the guides above the surface of the platform to prevent ink contamination thereof.
13. A wiping mechanism for a rotary intaglio printing machine comprising a mounting platform for wiping means, guide supports on the platform, a pair of brackets slidably mounted on the guides, an apron adapted to carry a wiping blade, and means to removably secure the apron to the brackets to facilitate access to the mounting platform.
14. A wiping mechanism for a rotary intaglio printing machine comprising a mounting platform for wiping means, guide supports on the platform, a reciprocable apron carrying a wiping blade and slidably mounted on the guides, a stud on the apron, and a cam carried by one of the guide members and having a driving engagement with the stud to effect reciprocation of the wiping blade.
15. A wiping mechanism for a rotary intaglio printing machine comprising a mounting platform for a wiping mechanism, guide members mounted on the platform, slide brackets mounted on the guides, an apron upon which a wiping blade is adapted to be mounted, means to removably fasten the apron to the brackets, a stud on the apron, and a cam carried by one of the guide members in driving engagement with the stud to reciprocate the wiping blade.
16. A wiping mechanism for a rotary intaglio printing machine comprising a mounting platform for a wiping mechanism, guide members mounted on the platform, slide brackets mounted on the guide members, an apron upon which a wiping blade is adapted to be mounted, means to removably fasten the apron to the brackets, a stud on the apron, a cam carried by one of the guide members in driving engagement with the stud to reciprocate the wiping blade, and means to mount the guide members, brackets, apron, stud and cam in a position which is spaced from the surface of the mounting platform.
17. A wiping mechanism for a rotary intaglio printing machine comprising a reciprocable slide carrying an apron and a wiping blade, a pressure apron pivotally mounted on the slide and having a pressure member adapted to urge the wiping blade into operative position, a cam shaft journaled in said pressure apron, cams mounted on said shaft to engage a surface carried by the slide, and means to rotate the shaft to vary the pressure of the pressure member on the wiping blade.
18. A wiping mechanism for a rotary intaglio printing machine comprising a reciprocable slide carrying an apron and a wiping blade, a pressure apron pivotally mounted on the slide and having a pressure member adapted to urge the wiping blade into operative position, a cam shaft journaled in said pressure apron, cams mounted on said shaft to engage a surface carried by the slide, means to rotate the shaft to vary the pressure of the pressure member on the wiping blade,
- and a pressure indicator to indicate the position of the pressure member.
19. A wiping mechanism for a rotary intaglio printing machine comprising a reciprocable slide carrying a wiping blade, a pressure apron cover pivotally mounted on the slide and having a pressure member adapted to urge the wiping blade into operative position, a cam shaft journaled in said apron, cams mounted on said shaft to engage the slide, means to rotate the shaft to vary the pressure of the pressure member on the wiping blade, a pressure indicator to indicate the position of the pressure member, and means to limit the movement of the pressure member.
20. A wiping mechanism for a rotary intaglio printing machine comprising a reciprocable slide carrying a wiping blade, a pressure apron cover pivotally mounted on the slide and having a pressure member adapted to urge the wiping blade into operative position, a cam shaft journaled in said apron, cams mounted on said shaft to engage the slide, means to rotate the shaft to vary the pressure of the pressure member on the wiping blade, a pressure indicator to indicate the position of the pressure member, and adjustable means to limit the movement of the pressure member.
21. A wiping mechanism for a rotary intaglio printing machine comprising a reciprocable slide carrying a wiping blade, a pair of links pivotally mounted on said slide, a pressure apron cover hingedly mounted by the links, and locking means to prevent movement of the links with respect to the slide.
22. A wiping mechanism for a rotary intaglio printing machine comprising a reciprocable slide carrying an apron and a wiping blade, a pair of links pivotally mounted on said slide, a pressure apron hingedly mounted by the links, and locking means to prevent movement of the links with respect to the slide, said locking means comprising lock plungers constituting fulcrum shafts for the apron in the links.
23. A wiping mechanism for a rotary intaglio printing machine comprising a reciprocable slide carrying an apron and a wiping blade, a pair of links pivotally mounted on said slide, a pressure apron hingedly mounted by the links, locking means to prevent movement of the links with respect to the slide, said locking means comprising lock plungers constituting fulcrum shafts for the pressure apron in the links, and means on the exterior of the pressure apron for operating the locking means.
24. A wiping mechanism for a rotary intaglio printing machine comprising a reciprocable slide carrying a wiping blade, an apron cover carrying a pressure member for urging the wiping blade into operative wiping position, a double fulcrum mechanism for mounting the cover on the slide, locking means to prevent pivotal movement about one of the fulcrums, adjusting means to control the pivotal movement of the pressure member about the other of the fulcrums, and separate means mounted on the cover and accessible on the exterior thereof to operate the locking means and the adjusting means respectively.
25. Housing structure for a rotary intaglio printing machine having an enclosed ink housing chamber including a stationary side wall, a hinged side wall portion pivotally mounted thereon, cooperating longitudinally extending sealing surfaces on the walls, a movable wall plate adapted to form an adjustable member in sealing con-

- tiguity with the hinged plate, cooperating guide members on the hinged wall portion and movable wall plate and means to mount said guide members out of contact with the interior of the housing.
26. Sealing mechanism for a rotary intaglio printing machine having an enclosed ink housing chamber and a doctor comprising adjustable end sealing members to seal the space between the 10 end walls of the ink housing and the ends of the cylinder, the ends of said members having an abutting sealing engagement with the doctor at the wiping edge thereof.
27. Sealing mechanism for a rotary intaglio printing machine having an enclosed ink housing chamber and a doctor comprising end sealing members to seal the space between the end walls of the ink housing and the ends of the cylinder, said members including a stationary member 15 mounted on the end wall of the housing, a movable member cooperating with the stationary member, and means to adjust the position of the movable member with respect to the stationary member, the movable member being adapted to 20 lie in abutting sealing engagement with the wiping edge of the doctor.
28. Sealing mechanism for a rotary intaglio printing machine having an enclosed ink housing chamber and a doctor comprising end sealing 30 members to seal the space between the end walls of the ink housing and the ends of the cylinder, said members including a stationary member mounted on the end wall of the housing, an arcuate guide member on the stationary member, and 35 a movable member on the arcuate member and in sealing relation therewith, the movable member being adapted to lie in abutting sealing engagement with the wiping edge of the doctor.
29. Sealing mechanism for a rotary intaglio printing machine having an enclosed ink housing chamber comprising a longitudinal sealing strip on the inking side of the machine, a doctor on the wiping side, and end sealing means for sealing 40 the space between the end walls of the housing and the ends of the printing cylinder, said last named means having an overlapping sealing engagement with the sealing strip and the ends of said end sealing means having an abutting sealing engagement with the doctor.
30. Means for sealing the end of an ink housing for rotary intaglio printing machines having rotatable printing cylinders comprising a housing end wall, an end sealing member adapted to 45 provide a seal between the housing end wall and the adjacent end of the cylinder, and means to position the sealing member adjustably.
31. Means for sealing the end of an ink housing for rotary intaglio printing machines having rotatable printing cylinders comprising a housing
- end wall, an end sealing member adapted to provide a seal between the housing end wall and the adjacent end of the cylinder, means to mount the sealing member slidably, and means to move the sealing member.
32. Means for sealing the end of an ink housing for rotary intaglio printing machines having rotatable printing cylinders comprising a housing end wall, an arcuate end sealing member adapted to provide a seal between the housing end wall and the adjacent end of the cylinder, and means to mount the sealing member for arcuate sliding motion.
33. Means for sealing the end of an ink housing for rotary intaglio printing machines having 15 rotatable printing cylinders comprising a housing end wall, an arcuate end sealing member adapted to provide a seal between the housing end wall and the adjacent end of the cylinder, means to 20 mount the sealing member for arcuate sliding motion, and means to move the sealing member in an arcuate path adjustably.
34. Means for sealing the end of an ink housing for rotary intaglio printing machines having 25 rotatable printing cylinders comprising a housing end wall, an arcuate end sealing member adapted to provide a seal between the housing end wall and the adjacent end of the cylinder, an arcuate bracket on the end wall to mount the 30 sealing member slidably, and means to move the sealing member on the bracket.
35. In combination with an ink housing for a rotary intaglio printing machine having an end wall, a rotatable cylinder in the housing, a sealing strip at one side of the housing in sealing 35 contiguity with the cylinder, housing and end wall, a reciprocable doctor at the other side of the housing engaging the cylinder, an end sealing member on the housing end wall and in sealing contiguity with the end wall, sealing strip and 40 cylinder, and adjustable means to position the sealing member in sealing contiguity with the doctor.
36. In combination with an ink housing for a rotary intaglio printing machine having an end 45 wall, a rotatable cylinder in the housing, a sealing strip at one side of the housing in sealing contiguity with the cylinder, housing, and end wall, a reciprocable doctor at the other side of the housing engaging the cylinder, a relatively 50 fixed sealing blade under the doctor and in sealing contiguity with the end wall and the doctor, an end sealing member on the housing end wall and in sealing contiguity with the end wall, sealing strip and cylinder, and adjustable means to 55 position the sealing member in sealing contiguity with the sealing blade.

ADOLPH WEISS.

CERTIFICATE OF CORRECTION.

Patent No. 2,115,376.

April 26, 1938.

ADOLPH WEISS.

It is hereby certified that error appears in the printed specification of the above numbered patent requiring correction as follows: Page 3, second column, line 63, for the reference numeral "9" read 99; page 7, second column, line 43, claim 22, before "apron" insert the word pressure; and that the said Letters Patent should be read with these corrections therein that the same may conform to the record of the case in the Patent Office.

Signed and sealed this 31st day of May, A. D. 1938.

(Seal)

Henry Van Arsdale,
Acting Commissioner of Patents.
